PROTECTIVE BIB

Helen Campbell Reid, Summit, N. J.

Application May 28, 1952, Serial No. 290,400

2 Claims. (Cl. 2—49)

The present invention relates to a novel protective bib adapted to catch food and liquid that may be dropped by the wearer of said bib and thus prevent said food and liquid from falling into the lap of the individual or on the chair or floor.

Objects and advantages of the invention will be set forth in part hereinafter and in part will be obvious herefrom, or may be learned by practice with the invention, the same being realized and attained by means of the combinations and improvements pointed out in the appended claims.

The invention consists in the novel parts, constructions, arrangements, combinations and improvements herein shown and described.

An object of the present invention is to provide a novel bib wherein the body and pocket of the bib are integral so that a strong, durable bib is obtained which is free of leaking or tearing or other structural weakness.

A further object of my invention is to provide a bib which is free of any metal fastening means or any other dangerous protruding means.

Another object of my invention is to provide a novel bib of unitary construction which is flexible, comfortable to wear, sanitary and easily washable.

A further object of my invention is to provide a novel bib which may be readily made from a simple pattern to suit the wearer whether it be an infant or an adult.

Another object of my invention is to provide a novel bib having a pocket which extends laterally of the back of the bib thus providing a pocket of larger catching area than is present in any of the presently known bibs.

A further object of my invention is to provide a novel pattern adapted to be used in combination with a folded sheet of material in forming an outline of material, said outline of material being subsequently used in forming a novel bib.

The accompanying drawings, referred to herein and constituting a part hereof illustrate an embodiment of the invention and, together with the description, serve to explain the principles of the invention.

Figure 1 is a side perspective view of an embodiment of my novel bib.

Figure 2 is a front elevational view of the bib shown in Figure 1.

Figure 3 is a sectional view on line 3—3 of Figure 2.

Figure 4 is a plan view of the pattern used in forming the outline of material utilized in making the bib of Figure 1.

The conventional bibs on the market today usually consist of a body portion having a separate pocket member connected thereto at its lower end by various fastening means such as metal clips, interlocking parts, seams, binders, etc. Due to such two-part construction, these bibs very often come apart and leak after a relatively short period of use, due to the loosening of the fastening means, thus necessitating purchase of a new bib or repairing the old one. Furthermore, in a bib having a two-part body and pocket construction as described above, it is very difficult to cleanse the pocket properly due to the cumbersome construction of the bib. Hence, tiny food particles accumulate in the insufficiently cleansed pocket, said food particles deteriorating and decaying and causing unsanitary conditions, due to growth of bacteria, mold and other infestations. This is especially unfortunate when such bibs are used by infants, who are more susceptible to infections than adults.

Moreover, bibs which utilize metal fastening means such as metal clips, etc., are physically hazardous for infants, providing dangerous projections or loose foreign objects which can be swallowed.

In order to overcome the disadvantages of presently known bibs, I have invented a bib which is relatively simple to make but which is entirely sanitary, easy to clean and safe to use. My novel bib comprises a body member having a neckline at its upper edge and an integral gathered pocket member extending outwardly from said body member. The gathered ends of said pocket member are connected by a binder strip, said binder strip having one end connected to the body member adjacent one end of the neckline and extending around the edge of the pocket so that its other end is connected to said body member adjacent the other end of said neckline. Preferably, the neckline of the body member is strengthened with an overlying binder strip having extended end portions which form ties which are used as ties to fasten the bib about the neck. Advantageously, the sides of the pocket member extend laterally below the ends of the neckline which results in the formation of an extremely wide pocket which not only catches food dropping directly from the mouth of the wearer but also provides a wide safety area for catching food dropping from anywhere above said catching area.

In forming the bib having such integral body and pocket member, I employ a half pattern having a straight line edge which is connected to a first curved neckline edge at one end and a second curved edge adapted to be gathered at the other end, the dimension of the straight line edge being substantially greater than said first curved edge or neckline edge but less than said second curved edge. Accordingly, the pattern is placed on top of a sheet of material folded in two with the straight line edge of the pattern being placed in the same vertical plane as the folded edge of the material adapted to be cut to the desired outline. The material is then cut along the curved edges of the pattern whereby on the unfolding of the cut out material the desired outline of an integral sheet of material is obtained from which the body member and gathered pocket member can be formed.

The material is then gathered along most of the larger curved edge and the gathered edges are then connected by a suitable binder strip which extends from one end of the neckline or smaller curved edge to the other end of said neckline. This binder strip may be connected to the gathered edges in any suitable manner such as by stitching, adhesive means, etc. Of course, the material may be gathered along the entire edge if so desired, but it has been found satisfactory merely to pleat along a greater part of said edge leaving a minor portion at both ends ungathered. Also, since the neckline is preferably provided with a binder strip, it is less cumbersome to leave a minor unpleated portion adjacent each end of the larger curved edge. The binder strip which overlies the neckline of the body member may be connected to said body member in any desired fashion such as by stitching, adhesive means, etc.

Any suitable flexible sheet material may be used in making my bib as, for example, silk, plastic fabrics, etc. Preferably, the material should be waterproof. Likewise, the binder strip used in connecting the gathered edges, as well as the binder strip used in strengthening the neckline and in forming the ties, is preferably cut from the unused material after the body and pocket material has been cut. By this construction, the entire bib is made from the same material which not only produces a bib which is extremely attractive in appearance but also provides a conservation of material which lessens the cost.

In order to describe the invention more specifically, reference is now made to the accompanying drawings. As shown in Figures 1-3, my bib consists of a body member 1 and an integral gathered pocket portion 2, the body member and pocket member forming a continuous surface at 3. Connecting the gathered edges 4 is a binder strip 5 which begins at 6, extends around the edge of the pocket and ends at 7. Overlying the neckline 8 of the body member 1 is another binder strip 9 having extended end portions 10 and 11 forming ties for suspending the bib from the neck.

in Figure 4, a half pattern 12 utilized in forming the necessary outline of material for making the bib shown in Figures 1-3 is illustrated. The half pattern 12 has a straight line edge 13, a small curved neckline edge 14 and a substantially larger curved edge 15, said neckline edge 14 curving upwardly and outwardly from end 16 of edge 13 with said edge 15 curving outwardly and downwardly from the end 17 of edge 14 and then downwardly and inwardly to meet end 18 of edge 13. As mentioned previously, the dimension of edge 13 should be substantially greater than the dimension of edge 14, but less than edge 15. A preferred ratio of the dimensions of the straight line edge 13 to the curved edge 14 and curved edge 15 is in the ratio of about 3.5:1:9.5.

As mentioned previously, the pattern 12 is placed on top of the material adapted to be cut, said material being folded in two with the straight line edge 13 in the same vertical plane as the folded edge of said material. The material is then cut along edges 14 and 15 thus producing the desired outline when the cut out material is unfolded. The edge of the material produced by cutting along the edge 15 of the pattern is then gathered throughout a major portion, leaving minor portions adjacent the ends of said edge ungathered for reasons previously mentioned. In this manner, edges 4 are formed which are connected by means of the binder strip 5 by sewing said binder strip to said gathered portions. A binder strip 9 is then sewed to the body member 1 so as to overlie the neckline 8 with the extended portions 10 and 11 of said binder strip 9 forming ties as previously mentioned.

By means of the present construction, the pocket 2 is of an extremely large width due to the fact that the side members 19 and 20 of said pocket 2 extend laterally of the ends of the neckline area. Thus a large catching area is provided by which most efficient catching results are obtained.

There is no doubt that the present invention is a step forward in its field. Since my bib is flexible and has integral body and pocket members, the pocket member may be readily turned inside out so that the pocket may be cleansed properly, which prevents any accumulation of food particles which would decay in said pocket. Hence, my bib is most sanitary and this is a very important feature especially where infants and invalids are concerned. The bib can also be used in reverse form if so desired.

Furthermore, my integral construction eliminates the use of metal clips or any other hazardous metal fastening means which are apt to be removed by an infant and put into its mouth. It is also evident that a much stronger and durable bib is produced by my integral construction in contrast to the two part conventional constructions wherein the fastening means very often loosen or come apart completely, thus causing the pocket to

leak or tear, and necessitating purchase of a new bib or, at least, repair of the old one.

Also, by providing a bib with a catching pocket of an extremely large width, a greater catching area is produced which in turn insures greater catching safety. This is particularly advantageous in use by infants since they very often pick up food with their hands and soon after drop it before the food ever reaches their mouths.

It is also evident that the bib of the present invention is inexpensive to make due to its simple construction and ease of manufacture.

In view of the fact that the present bib is highly useful, most sanitary, attractive in appearance, simple in construction and low in cost, it may be safely said that the present invention is a decided contribution to the art.

The invention in its broader aspects is not limited to the specific combinations and improvements described, but departures may be made therefrom within the scope of the accompanying claims without departing from the principles of the invention and without sacrificing its chief advantages.

What I claim is:

1. A bib comprising a unitary sheet of flexible, waterproof material provided with a very shallow U-shaped edge defining a neckline at its top and a very deep U-shaped edge lying forwardly and downwardly from said shallow edge for defining the top of a pocket, said deep edge forming a juncture with said shallow edge at each end thereof, tying means positioned adjacent each of said junctures for fastening said bib on a child, said deep U-shaped edge being provided with a plurality of gathers along the bottom of the U and up each leg thereof for a substantial distance, the gathers being sufficient in number and width to cause a portion of said sheet to fold upon itself, the gathers and the folded portion being substantially co-extensive, whereby a reversible, integral, seamless and sanitary pocket is formed forwardly from the bottom and along the sides of said bib.
2. A bib as defined in claim 1 which includes in addition a substantially non-resilient strip binding said gathered edge for preserving the shape of said pocket.
